GAME APPARATUS

Robert P. Shelton, Fairfield, Conn.

Application August 4, 1938, Serial No. 223,021

5 Claims. (Cl. 273—100)

The present invention relates to an improvement in game apparatus, and particularly one which may be classed as a game of skill, as distinguished from games of chance. While it will be obvious from the following description that the game may find use in numerous places, and for various purposes, the following uses may be pointed out particularly: (1) Use in the home for purely entertainment purposes; (2) use in schools for educational purposes; (3) use in hospitals or similar institutions by patients undergoing physical or mental therapy treatment, where physical effort and mental concentration are factors in such treatment; and (4) use in public places such as carnivals, amusement parks, and the like. It will also be obvious that the game may be played by one player, or several of the games may be played simultaneously and competitively by several players.

It is particularly proposed to provide a game which may simulate various events, as for instance, a round the world flight, or other undertaking where progress may be measured in various steps, in other words, in a round the world flight the steps will represent the various stops. It is proposed to provide means whereby such steps in the game will require greater or less skill, and which may be compared to the difficulty encountered at different points in the flight or other undertaking that the game simulates. In the case of simulation of an around the world flight, the board will contain a map representation which will have the educational functions of giving instruction in the names and location of various countries and cities.

In carrying out my invention, I propose to employ at each stop a peg which the player endeavors to ring or engage by means of a ring or other suitable device, carried upon the end of a cord, wire or the like, which in turn is suspended from the end of a wand or stick, such wand or stick being provided with means which will compel the player to hold it at a predetermined distance from the end thereby standardizing the conditions of play required by each player, and also standardizing the conditions for ringing the pegs at each stop.

It is further proposed to provide the pegs at the different stops of various heights, and which will require various degrees of skill in ringing it in order to engage the ring with them. It is further proposed to provide, as one form of the invention, a surface surrounding the peg which will have a varying contour so that different degrees of skill will be required depending upon the

point at which it is tried to engage the ring, and such surface contour may be in the nature of an obstruction or hazard, simulating, for instance, trees, telephone wires, etc.

A further object is to provide a game apparatus of this type in which timing means will be co-ordinated with the game, so that the player's time in completing the course may be scored. Where a number of games are played simultaneously and competitively by several players the first to finish will be considered the winner, irrespective of time.

A further object is to provide a game apparatus of simple and inexpensive construction, in which the parts may be readily removed and replaced, in the event of breakage or wear.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a perspective view showing the game apparatus according to the invention.

Fig. 2 is a front elevation showing one form of ring according to the invention.

Fig. 3 is an edge view thereof.

Fig. 4 is a sectional view showing one of the pegs and which is of cylindrical cross-section.

Fig. 5 is a similar view showing a modified form of peg, and which is of square or triangular or other cross-section.

Fig. 6 is a sectional view showing the ring also in section, in position to be engaged with the peg, the peg shown in this view being relatively high and requiring a relatively high degree of skill to engage the ring therewith.

Fig. 7 is a similar view showing a shorter peg, and which requires a lesser degree of skill than the peg as shown in Fig. 6.

Fig. 8 is a sectional view of a modification in which the contour of the board surrounding the peg is in the form of a "hill" at one side and a "valley" at the other, the dot and dash lines showing the relative positions of the ring as the player endeavors to ring the peg.

Fig. 9 is a sectional view showing a board or portion of the board of convex form.

Fig. 10 is a sectional view showing a board or portion of the board of concave form.

Figs. 11 to 16 inclusive, show various modifications of the ring.

Fig. 17 is a vertical sectional view of the modification of the ring as shown in Fig. 16.

Similar reference characters indicate corresponding parts throughout the several figures of the drawing.

Referring to the drawing, the game apparatus, according to the illustrated exemplary embodiment of the invention, comprises a suitable playing board or field 10, consisting of a rectangular or other suitably shaped panel, which may be formed of ply-wood, press board, metal, or other suitable material, as will be obvious. Supporting cleats 11 and 12 are preferably secured adjacent the side edges at the underside of the board, and at the forward end at the upper side there is provided a board strip 13 having a pocket 14 therein in which is engaged a stop watch 15, or other suitable timing device. The pocket 14 has an open slot 16, in which the manipulating handle of the stop watch is engaged and which will permit it to be conveniently started and stopped.

The game illustrated simulates a round-the-world flight, although it will be understood that the invention is not limited to this particular type of situation, it being understood that any suitable event in which step-by-step progress is made may be simulated. In the case of a round-the-world flight, as illustrated, a map 17 is depicted, and this shows various cities which are stops in the flight, the cities being indicated by circles 18 printed on the board and the name of the particular cities, and the course of the flight being indicated by arrow lines 19 extending between the cities.

At each city indication, or other stop in the game, there is provided a peg 20, preferably vertically disposed, although it may if desired be at an angle, and which is secured in the board in any suitable manner, preferably by having the lower end of the peg threaded, as at 21, and engaged in a threaded hole 22 in the board, to the end that the peg may be conveniently assembled with the board, may be readily removed and replaced in the case of damage, and may be adjusted as to height. It is a feature of the game, as will presently more fully appear, that the pegs be of different heights, as the difficulty and ease of ringing the pegs varies in direct proportion to the height of the peg, so that cities or other stops in the game will be of such height as to simulate the actual landing or other conditions of the flight, or other undertaking at such cities or stops. For instance, in the case of a round-the-world flight, the city of Omsk may be considered as a more difficult landing place than the city of New York, in which case the peg representing the city of Omsk will be higher than the peg representing the city of New York. Inasmuch as the difference in height is not readily perceptible to the player, this feature adds an element of surprise, as the player finds it considerably harder to ring such higher peg after having rung a shorter peg with comparative ease.

The pegs may be of any suitable cross-section, as for instance cylindrical as shown in Fig. 4, or of square or triangular cross section, as shown at 20^a, Fig. 5. Other cross-sections such as semi-circular, oval, octagonal or the like may be employed, but it is not considered necessary that all of these be illustrated. In addition to varying the cross-section of the peg, it will be understood that the upper end may be varied, that is, it may be pointed, as shown, it may be rounded, or it may be flat or otherwise suitably shaped.

The ringing device consists of a wand or stick 23, preferably rigid and provided with a guard or hilt 24, adjacent the handle 25, this guard or

hilt compelling the player to manipulate the wand by the handle end and at a predetermined distance from the outer end of the wand or stick. It will be understood that without such guard the player might be enabled to grip the wand at different distances from the outer end which will change the condition under which the ring is manipulated. The guard therefore standardizes the conditions under which the ringing device is manipulated by each player, and at each stop. Secured to the outer end of the wand 23 is a cord or wire 26 and to the lower end of this cord or wire there is secured the circular ring 27 provided with a central circular hole 28. As shown in Figs. 2 and 3 the cord is secured to the ring by looping it through a hole 29 near the edge of the ring and knotting as at 30.

The diameter of the ring, as well as the size and diameter of the hole 28, is designed in relation to the height of the peg, so that the ease or difficulty of ringing the peg will vary directly with the height of the peg. As shown in Fig. 6 the peg is higher than the top point of the hole 28, and it will be found that it is comparatively difficult to ring the peg under these conditions, and that scientific methods may be employed to accomplish it. As the ring is drawn into relation with the peg the engagement of the upper end of the peg with the ring above the hole 28 will cause the ring to lift off of the base and shift to one side or the other, so that considerable skill is required in order to drag, flip, or otherwise scientifically manipulate it, with the aid of careful balancing and attention to component vectors, to cause the ring to engage over the peg. As shown in Fig. 7 the peg is shorter than the top point of the hole and the ring may be engaged therewith with comparative ease, simply by dragging it against the peg.

In Fig. 8 I have shown a modification of the board in which the contour of the upper surface is similar to a relief map, there being a hill like surface 31 at one side of the peg, and a valley like surface 32 at the other side. It will be obvious that such variation in the surface contour of the board may be designed to represent mountains, hills, or other obstructions, and may be either contiguous to the peg, as shown, or may be at a distance therefrom, in which latter case they will be designed as obstructions or hazards, such as forests, mountains, telegraph wires, or the like, that would affect the approach to a landing field. The arrangement of the hill and valley contiguous to the peg is such that the difficulty or ease with which the same may be rung is affected, it being easier to engage the ring by approaching the peg from the hill side than if it is approached from the valley side, the height of the peg in relation to the hole in the ring being shorter in the one case than the other. The dot-and-dash lines show the relative positions of the ring at the hill and valley sides of the peg.

In Fig. 9 I have shown a modified form of board 10 having a convex surface 33. Such convexity may extend over the hole of the board, representing, for instance, a convex representation of a map globe, or such convexity may be provided only at a portion of the board in surrounding relation to the peg.

In Fig. 10 I have shown a modified form of board 10 having a concave surface 34.

In Fig. 11 I have shown a modified form of ring 35 of triangular form and having a triangular hole 36 therein having its edges parallel to the outer edges of the ring. In Fig. 12 I have

shown a similarly shaped ring 37 having a circular hole 38.

In Fig. 13 I have shown a circular ring 39 having a diagonally disposed slot-like hole 40 therein.

In Fig. 14 I have shown a ring 41 of kite-like shape having a hole 42 of semi-circular shape. I have also shown above the hole 42 and along the center line of the ring a groove 43, which may be provided therein for the purpose of guiding the ring with respect to the peg after it has been engaged therewith. Such groove may be provided at one side only of the ring, in which case it will be easier to engage it with the ring if this side is brought into engagement with the peg rather than the plain side.

In Fig. 15 I have shown a circular ring 27 and having the cord 26 secured thereto by a hitch 44, carried about the ring and knotted at 45. This hitch will function as a guide groove.

In Figs. 16 and 17 I have shown a circular ring 27 and provided at each side with radial grooves 46, and in which a loop 47 of the cord 26 is engaged, and secured by knotting at 48, the arrangement being such that the cord is below the surface of the ring, and at the same time the groove constitutes a guide means for assistance in engaging the peg.

It will be obvious from the foregoing that the shape of the ring and the hole provided therein, as well as the means for attaching the cord may be varied, as desired, and that the surface of the ring may be provided with a groove or grooves arranged either to assist or hinder the engagement of the ring with the peg.

In playing the game the player will start at a given starting point, for instance New York as shown in the illustrated embodiment, and will endeavor to ring the pegs in sequence, the stop watch being started at the beginning of the game and stopped when the player has completed the circuit. The rules may be such that in order to win the player must make the circuit within a given time, as for instance, one minute. Where two or more games are played competitively between two or more players, the first to complete the circuit will be considered the winner. It will be understood that the height of the pegs, the shape of the ring, the length of the cord, the length of the wand, and the contour of the surface surrounding the peg may be varied, and that such variation will affect the difficulty or ease of ringing the pegs. In this way the game may be scientifically designed to meet the different uses contemplated. For instance, where the game is to be used in hospitals or similar institutions for physical or mental therapy treatment, it will preferably be so designed that the pegs may be engaged with comparative ease, this being especially desirable in the case of certain types of patients. In the case of the game

being used for purely entertainment or competitive purposes the various factors will be designed to make it comparatively difficult.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:

1. In a game apparatus for use with a wand controlled apertured ringing device having predetermined outer and inner diameters, a playing field board, a series of spaced sequential stop means upon said playing field, each consisting of an upstanding peg member secured to said board, certain of said pegs being relatively higher than others, the upper ends of said higher pegs adapted to engage said ringing device when the latter is leaned against said peg at a point between the top of the aperture and the top of the outer edge of the ringing device, and the upper ends of said relatively shorter pegs being in line with a portion of said aperture when said ringing device is in leaning relation with respect to the said peg.

2. In a game apparatus for use with a wand controlled apertured ringing device, a playing field board, a series of spaced sequentially arranged stop means upon said playing field, each consisting of an upstanding peg member secured to said board, said playing field having a non-flat surface in surrounding relation to at least one side of said peg.

3. In a game apparatus for use with a wand controlled apertured ringing device, a playing field board, a series of spaced sequentially arranged stop means upon said playing field, each consisting of an upstanding peg member secured to said board, said playing field having a hill and valley surface in surrounding relation to at least one side of said peg, the hill being at one side and the valley at the other.

4. In a game apparatus for use with a wand controlled apertured ringing device, a playing field board, a series of spaced sequentially arranged stop means upon said playing field, each consisting of an upstanding peg member secured to said board, said playing field having a convex surface in surrounding relation to at least one of said pegs.

5. In a game apparatus for use with a wand controlled apertured ringing device, a playing field board, a series of spaced sequentially arranged stop means upon said playing field, each consisting of an upstanding peg member secured to said board, said playing field having a concave surface in surrounding relation to at least one of said pegs.

ROBERT P. SHELTON.
